US00D653669S

(12) **United States Design Patent**
Kim et al.

(10) **Patent No.:** **US D653,669 S**
(45) **Date of Patent:** **** Feb. 7, 2012**

(54) **CRADLE FOR NOTEBOOK COMPUTER**

(75) Inventors: **Dae-Joung Kim**, Seoul (KR); **Woo-Seok Lee**, Seoul (KR); **Sang-Il Park**, Kyunggi-do (KR); **Soo-Jung Ham**, Seoul (KR)

(73) Assignee: **Samsung Electronics Co., Ltd.**, Suwon (KR)

(**) Term: **14 Years**

(21) Appl. No.: **29/390,418**

(22) Filed: **Apr. 25, 2011**

(30) **Foreign Application Priority Data**

Dec. 23, 2010 (KR) 30-2010-0055468

(51) **LOC (9) Cl.** **14-02**

(57) **CLAIM**

The ornamental design for a cradle for notebook computer, as shown and described.

DESCRIPTION

FIG. 1 is a top front perspective view of a cradle for notebook computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
